UNITED STATES PATENT OFFICE.

HAROLD O. HOLTE, OF PITTSBURGH, PENNSYLVANIA; HALVOR HOLTE, SPECIAL ADMINISTRATOR OF SAID HAROLD O. HOLTE, DECEASED, ASSIGNOR TO THE UNION SWITCH & SIGNAL COMPANY, OF SWISSVALE, PENNSYLVANIA, A CORPORATION OF PENNSYLVANIA.

TRAIN-CARRIED RECEIVER FOR AUTOMATIC TRAIN-CONTROL SYSTEMS.

Application filed March 19, 1926. Serial No. 95,922.

My invention relates to automatic train control systems of the type wherein train carried apparatus is controlled at least in part by alternating train controlling currents which flow through the track rails. More specifically, my present invention relates to train carried receivers for use in systems of this character.

One object of my invention is the provision of a receiver which will supply energy to the train carried apparatus in accordance with the train controlling current in the rails, but which will not supply energy to such apparatus in accordance with alternating currents flowing in adjacent transmission lines or in adjacent tracks, etc.

I will describe two forms of receivers embodying my invention, and will then point out the novel features thereof in claims.

In the accompanying drawings, Fig. 1 is a view, partly diagrammatic, showing one form of train carried receiver embodying my invention. Fig. 2 is a view illustrating one modification of the receiver shown in Fig. 1 and also embodying my invention. Figs. 3 and 4 are views showing, in top plan and front elevation, respectively, the complete receiver A illustrated diagrammatically in Figs. 1 and 2. Fig. 5 is a diagrammatic view showing a portion of an automatic train control system including receivers embodying my invention.

Similar reference characters refer to similar parts in each of the several views.

Referring first to Fig. 5, the reference characters 1 and 1^a designate the track rails of a railway, which rails are divided by insulated joints 2 to form a track section. Connected across the rails of this section at spaced points are two resistances 3 and 3^a, and connected with the middle points of these two resistances, respectively, are the two terminals of the secondary 7 of a loop transformer T. The primary 6 of this transformer is supplied with alternating train controlling current from a suitable source not shown in the drawing. It will be apparent that the current supplied by transformer T flows through the two track rails 1 and 1^a in multiple, that is, at any instant, it flows in the same direction in the

two rails. I shall call the train controlling current thus supplied to the trackway "loop" current.

Means are also provided for supplying track circuit current to the rails of the track section. For this purpose a track transformer, designated by the reference character J, has its secondary 4 connected across the rails adjacent one end of the section. The primary 5 of transformer J is constantly supplied with alternating current from a suitable source not shown in the drawing. The track circuit current supplied to the rails by transformer J may be used to control governing means of any suitable form which may include a track relay Q connected across the rails adjacent the opposite end of the section. The track circuit current supplied to the rails by transformer J flows through the rails 1 and 1^a in opposite directions at any given instant.

The reference character W designates a railway train provided with receivers A and A¹ embodying my invention. Referring to Fig. 1, receiver A comprises a member S of magnetizable material extending transversely across the two track rails 1 and 1^a and made up of three sections, 8, 9 and 10. The ends of sections 8 and 9 are separated by an air gap 14, and sections 9 and 10 are spaced apart by an air gap 15. The receiver A comprises also four downwardly projecting legs, 16, 17, 18, and 19, so disposed that the legs 16 and 17 are on opposite sides of one track rail 1^a and the legs 18 and 19 are on opposite sides of the other track rail 1. Legs 17 and 18 are spaced from the ends of section 9 of member S by air gaps 25 and 26, respectively. In similar fashion leg 16 is spaced from section 8 by air gap 24, and leg 19 is spaced from section 10 by an air gap 27. Legs 17 and 18 are provided with feet 28 and 29 spaced from the corresponding legs by air gaps 30 and 31, respectively, and extending in a direction parallel to the track rails as best shown in Fig. 5. The four legs 16, 17, 18 and 19 carry a winding which is made up of four coils 20, 21, 22 and 23 located upon the four legs, respectively. This winding is included in a pick-up circuit, B and since the receiver illustrated in Fig. 1 is intended to supply current to

the train carried apparatus in accordance with the loop current in the trackway, the four coils of the receiver are connected in series in the pick-up circuit in such manner that the polarities of the coils on each two adjacent legs are opposite. The pick-up circuit also includes a condenser 38 which will usually be adjusted to balance the inductive reactance of the circuit B, so that the circuit 10 is tuned to resonance at the frequency of the loop current supplied to the track rails from transformer T.

The pick-up circuit B may be used in connection with train carried governing apparatus of any suitable type. As here shown this circuit supplies energy to one winding 39 of an induction motor relay R, the other winding 40 of which is supplied with energy by any suitable means such for example as the track circuit current receiver A¹ herein-after described. An amplifier is preferably interposed between the receiver circuit B and the winding 39. As here shown the amplifier is connected across the terminals of the condenser 38.

The magnetic flux surrounding the rails 1 and 1^a due to the loop current in these rails may be represented by the broken lines in Fig. 1. The flux 36 surrounding rail 1 will pass through coils 22 and 23 in such directions as to create electromotive forces in the circuit B which are additive. Similarly, the flux 36^a surrounding rail 1^a will flow through coils 20 and 21 in such directions as to create electromotive forces in the circuit B which are additive. Furthermore, the electromotive forces thus created in coils 20 and 21 by the one flux and in coils 22 and 23 by the other flux are additive. An electromotive force is therefore created across the terminals of condenser 38 due to the loop current flowing in the track rails.

The two rails will also be surrounded by a magnetic flux which may be represented by the broken line 37. This flux will flow through the coils 20 and 23 in such directions as to create electromotive forces in these coils which are additive to each other and which are also additive to the electromotive forces created by fluxes 36^a and 36 surrounding the individual track rails.

A horizontal foreign magnetic flux will pass partly along the member S and so will create no electromotive force in the windings of receiver A. In order to increase the proportion of the foreign flux which traverses this path through the receiver, I provide arms 12 and 13 which project from the ends of the member S. Another part of such foreign horizontal flux will enter the receiver at leg 16 and will leave at leg 19, whereas still another part will enter at leg 17 and leave at leg 18. These two last mentioned parts of the foreign flux will create opposite electromotive forces in the circuit B,

and by proper proportioning of the number of turns in the several coils and of the size of the feet 28 and 29, these two opposite electromotive forces can be made approximately equal so that they will have no effect upon the relay R. The foreign flux through the legs of the receiver is decreased by the air gaps 24, 25, 26 and 27 and also by the air gaps 30 and 31. The air gaps 14 and 15 cause a greater proportion of the horizontal foreign flux to traverse legs 17 and 18 than would otherwise be the case. But these two air gaps also decrease the effectiveness of the receiver in its response to loop current in the trackway and I have discovered that there is an optimum length for these air gaps for any given receiver. In the form shown in the drawing each of the sections 8, 9 and 10 of member S is 27½ inches long, and each of the legs 16, 17, 18 and 19 is 5 inches long. For a receiver having these proportions, I have discovered that the optimum length for the air gaps 14 and 15 is .06 inches.

The four air gaps 30, 25, 26 and 31 should be as small as possible and may, for example, be .01 inches. The length of each air gap 24 and 27 is preferably .015 inches.

With the receiver proportioned as just described I have found that if the ratio of the turns in coils 21 and 22 to the turns in coils 20 and 23 is 5 to 8, a uniform foreign horizontal flux will have substantially no effect upon the pick-up circuit B.

A vertical foreign flux will pass through all four legs of the receiver in the same direction, and the resulting electromotive forces induced in windings 20 and 21 are balanced by the electromotive forces induced in windings 23 and 22, respectively, so that the net effect of this vertical flux upon the pick-up circuit is substantially nil.

It follows from the foregoing that any foreign magnetic flux due to alternating current in a transmission line or an adjacent track will create little or no electromotive force in the pick-up circuit B, and so will have little or no tendency to cause false operation of the train governing relay R.

In a train control system of the type to which this invention relates, the receiver A is usually located between the engine and the tender of a steam train, and between the first and second car of an electric train. I have found that in some instances a portion of the loop current from transformer T will leave the rails at the forward end of the train, pass through the steel construction and couplers of the train, and return to the rails at the rear end of the train. Inasmuch as the receiver A is usually located under the coupler, it follows that this current which passes through the train itself, and which is usually termed the "coupler" current, will pass above the receiver A. When the receiver is constructed in accordance

with my invention, the magnetic flux surrounding the coupler will pass largely through the middle legs 17 and 18 of the receiver and so will create electromotive forces in the coils 21 and 22 which assist the electromotive forces induced in these coils by the current which remains in the track rails.

The various parts of the receiver may conveniently be assembled as shown in Figs. 3 and 4.

Referring to these views, the sections 8, 9 and 10 of the member S are mounted between members 11 and 11^a which extend the entire length of the receiver. The members 11 and 11^a are clamped together by a number of split housings 32, 33, 34 and 35, which housings surround legs 16, 17, 18 and 19 respectively and hold the legs in fixed positions with respect to the member S. These housings have the further function of protecting from the elements the coils which are placed upon these legs. The arms 12 and 13 are clamped in place by the housings 32 and 35. A bolt 41 passes through leg 17 and section 9 of bar S and is provided with a nut 41^a to hold foot 28 in its proper position. Similarly foot 29 is held in place by a bolt 42 passing through leg 18 and section 9 and provided with a nut 42^a. I prefer to make the members 11 and 11^a of cold rolled steel and the housings 32, 33, etc., of cast aluminum. It will therefore be seen that parallel magnetic paths are provided around the air gaps of the receiver. I prefer, however, to construct the sections 8, 9, 10 and the legs 16, 17, etc., of laminated soft iron so that substantially all the flux passes through these parts of greater permeability and the members 11 and 11^a and the housings 32, 33, etc., have substantially no tendency to interfere with the described effect of the air gap. It is manifest that with the receiver assembled as shown in the drawing the various parts can be permanently clamped in their proper positions so that the lengths of the air gaps have the required values.

Under some conditions of operation it is desirable to operate the relay R in accordance with the track circuit current, that is, the current supplied by transformer J in Fig. 1, instead of the loop current supplied by transformer T. With a receiver embodying my invention this can be accomplished by the simple expedient of inverting the coils associated with one rail. For example, as shown in Fig. 2 the receiver is similar to that shown in Fig. 1 except that coils 22 and 23 have been inverted. The flux 36^a surrounding rail 1^a passes through legs 16 and 17 and creates in coils 20 and 21 electromotive forces which are additive. The flux 36 surrounding rail 1 creates in coils 22 and 23 electromotive forces which

are additive to each other and which are also additive to the electromotive forces created in coils 20 and 21 by flux 36^a. Winding 40 of relay R is supplied with current in accordance with the track circuit current supplied to the track rails 1 and 1^a. A horizontal foreign flux will pass partly through the member S as explained hereinbefore, and this part of the flux will have no effect upon the receiver winding. Another part of this horizontal flux will enter the receiver at leg 16 and will leave at leg 19. Still another part of the foreign flux will enter at leg 17 and leave at leg 18. The part of the foreign flux which passes through legs 16 and 19 will induce in coils 20 and 23 electromotive forces which are in opposition to the electromotive forces induced in coils 21 and 22 by the part of the foreign flux which passes through legs 17 and 18.

Furthermore a vertical foreign flux will pass through all the coils in the same direction and the electromotive forces created by this foreign flux in coils 20 and 23 will oppose the electromotive forces created by this vertical foreign flux in coils 21 and 22. By properly proportioning the various parts I have discovered that the receiver can be made substantially immune to the effect of any foreign flux. With the magnetic structure shown in the drawing which is the same as that shown in Fig. 1, the ratio of turns in coils 21 and 22 to the turns in coils 20 and 23 is 7 to 4 for the receiver of Fig. 2. With the parts proportioned in this manner similar receivers may be used with the same turn ratios for receiving track circuit current when the coils are connected as shown in Fig. 2, and for receiving loop current when the coils are connected as shown in Fig. 1. In either case foreign flux will have substantially no effect upon the pick-up circuit B.

Although I have herein shown and described only two forms of train carried receivers for automatic train control systems embodying my invention, it is understood that various changes and modifications may be made therein within the scope of the appended claims without departing from the spirit and scope of my invention.

Having thus described my invention, what I claim is:

1. A train carried receiver comprising a member extending transversely across the track rails and having four downwardly projecting legs each spaced from said member by a small air gap, and a winding made up of a coil on each leg, said coils being connected in series in such manner that the electromotive forces induced therein by alternating currents in the track rails are additive.

2. A train carried receiver comprising a

member extending transversely across the track rails and having four downwardly projecting legs one on each side of each rail, the legs on opposite sides of each rail being spaced from said member by air gaps of different lengths, and a winding made up of a coil on each leg, said coils being connected in series in such manner that the electro-motive forces induced therein by alternating currents flowing in the track rails are additive.

3. A train carried receiver comprising a member extending transversely across the track rails and having four downwardly projecting legs each spaced from said member by a small air gap and two of such air gaps being of different length from the remaining air gaps, and a winding made up of a coil on each leg, said coils being connected in series in such manner that the polarities of the coils on each two adjacent legs are opposite.

4. A train carried receiver comprising a member extending transversely across the track rails and having four downwardly projecting legs, two magnetizable arms attached to the upper side of said member and extending outwardly from the ends thereof, and a winding made up of a coil on each said leg, said coils being connected in series.

5. A train carried receiver comprising a member extending transversely across the track rails and made up of three sections separated by air gaps, two legs downwardly projecting from the outer ends of the two outer sections, respectively, two legs downwardly projecting from the ends of the middle section, and a winding made up of a coil on each of said legs, said coils being connected in series.

6. A train carried receiver comprising a member extending transversely across the track rails and made up of a middle section and two outer sections separated by air gaps, two legs one projecting downwardly from the outer end of each said outer section and each spaced from the associated section by an air gap of one length, two other legs projecting downwardly from the ends of said middle section and separated therefrom by air gaps of a different length, and a winding made up of a coil on each said leg, said coils being connected in series.

7. A train carried receiver comprising a member extending transversely across the track rails and made up of a middle section and two outer sections separated by air gaps, two legs one projecting downwardly from the outer end of each said outer section and each spaced from the associated section by an air gap of one length, two other legs projecting downwardly from the ends of said middle section and separated therefrom by air gaps of a different length, two feet one depending from each of said last-mentioned

legs and each having a greater length in a direction parallel to the track rails than the corresponding dimension of the associated leg, and a winding made up of four coils one on each said leg, said coils being connected in series.

8. A train carried receiver comprising a member extending transversely across the track rails and made up of a middle section and two outer sections separated by air gaps, two legs one projecting downwardly from the outer end of each said outer section and each spaced from the associated section by an air gap, two other legs projecting downwardly from the ends of said middle section and each provided at its lower end with a foot having a greater length in a direction parallel to the track rails than the corresponding dimension of the associated leg, and a winding made up of four coils one on each said leg, said coils having different numbers of turns.

9. A train carried receiver comprising a member extending transversely across the track rails and made up of a middle section and two outer sections separated by air gaps, two legs, one projecting downwardly from the outer end of each said outer section and each spaced from the associated section by an air gap, two other legs projecting downwardly from the ends of said middle section and each provided at its lower end with a foot having a greater length in a direction parallel to the track rails than the corresponding dimension of the associated leg, and a winding made up of four coils one on each said leg all connected in series and the coils on the two first-mentioned legs having a smaller number of turns than the coils on the remaining legs.

10. A train carried receiver comprising a member extending transversely across the track rails and made up of a middle section and two outer sections separated by air gaps, two legs, one projecting downwardly from the outer end of each said outer section and each spaced from the associated section by an air gap, two other legs projecting downwardly from the ends of said middle section and each provided at its lower end with a foot having a greater length in a direction parallel to the track rails than the corresponding dimension of the associated leg, and a winding made up of four coils one on each leg all connected in series and the ratio of the turns in the coils on the two first-mentioned legs to the turns in the coils on the last-mentioned legs being substantially 5 to 8.

11. A train carried receiver comprising a member extending transversely across the track rails and made up of a middle section and two outer sections each substantially twenty-seven and one-half inches long separated by air gaps of substantially .06 inches,

two legs, each substantially five inches long and one projecting downwardly from the outer end of each said outer section and spaced therefrom by an air gap of substantially .015 inches, two other legs each substantially five inches long projecting downwardly from the two ends respectively of said middle section, and a winding made up of four coils one on each leg, said coils being connected in series in such manner that the electromotive forces induced therein by alternating currents flowing in the track rails are additive.

12. A train carried receiver comprising a member extending transversely across the track rails and made up of a middle section and two outer sections each substantially twenty-seven and one-half inches long separated by air gaps of substantially .06 inches,

two legs, each substantially five inches long 20 and one projecting downwardly from the outer end of each said outer section and spaced therefrom by an air gap of substantially .015 inches, two other legs each substantially five inches long projecting downwardly 25 from the two ends respectively of said middle section, and each provided at its lower end with a foot having a greater length in a direction parallel to the track rails than the corresponding dimension of 30 the associated leg, and a winding made up of four coils one on each leg, said coils being connected in series and the ratio of the turns in the coils on the two first-mentioned legs to the turns in the coils on the remaining 35 legs being substantially 5 to 8.

In testimony whereof I affix my signature.
HAROLD O. HOLTE.
